CLAIM

The ornamental design for a account balancing calculator, as shown and described.

DESCRIPTION

FIG. 1 is a front view of a account balancing calculator showing my new design.

FIG. 2 is a back view of the account balancing calculator.

FIG. 3 is a right side elevated view of the account balancing calculator.

FIG. 4 is a left side elevated view of the account balancing calculator.

FIG. 5 is a top view of the account balancing calculator; and, FIG. 6 is a bottom view of the account balancing calculator. The broken lines showing dollar amounts in the display areas on FIG. 1 are for illustrative purposes only and form no part of the claimed design.

1 Claim, 4 Drawing Sheets
